UNITED STATES PATENT OFFICE.

FREDERICK G. WHITTIER, OF BROOKLINE, MASSACHUSETTS, ASSIGNOR TO THE LAM-
SON COMPANY, OF BOSTON, MASSACHUSETTS, A CORPORATION OF NEW JERSEY.

ROUTING APPARATUS.

1,125,237.

Specification of Letters Patent. Patented Jan. 19, 1915.

Application filed October 28, 1912. Serial No. 728,049.

To all whom it may concern:

Be it known that I, FREDERICK G. WHITTIER, of Brookline, in the county of Norfolk and Commonwealth of Massachusetts, 5 have invented certain new and useful Improvements in Routing Apparatus, of which the following is a specification.

This invention relates to routing apparatus for use in department stores, express 10 offices and the like, where very large numbers of packages, bundles, etc., must be expeditiously and efficiently handled during relatively limited periods of time.

In business places of the above indicated 15 type, space is usually of very great importance and the package handling system should, in the first place, be as compact as possible. It further should, preferably, be adapted to deliver the goods to a plurality 20 of points where they may be conveniently marked by, for example, a number of employees of the establishment whose duty it is to label or mark upon the respective packages the symbol of the bin or repository into 25 which such packages are to be deposited, so that goods intended to be delivered to particular localities may be assembled in groups or batches preparatory to shipment.

It is highly desirable that the apparatus 30 be of simple construction and that it be adapted to deliver the packages to the points where they are to be labeled in substantially consecutive order so that the goods first conveyed to the routing table may in general be 35 the first to be labeled or handled, and so on.

The apparatus also should provide for a relatively slow movement of the packages over the table, and that substantially toward the labeling points or operatives rather than 40 laterally with respect to the same.

These and other objects of my invention 45 will be hereinafter referred to and the novel means and combinations of elements whereby they may be attained will be more particularly set forth in the claims appended hereto.

In the accompanying drawing, which forms a part hereof, I have shown several 50 forms of the apparatus in question but I am aware that various changes and modifications may be made therein without departing from the spirit of my invention and hence desire to be limited only by the scope of said claims.

55 Referring to the drawing, like reference

characters in which have been used to designate like parts in the respective views: Fig. 1 is a perspective view of a routing table constructed in accordance with the principles of my invention. Fig. 2 is a modification of the same: Fig. 3 is a further modification.

In the exemplification of the apparatus shown in Fig. 1, the table proper is provided with a sloping or inclined surface 1 which 60 is peculiarly well adapted to spread or distribute the parcels or packages, delivered thereto, toward the stations 2 at which said packages are labeled, stamped or otherwise treated. In the present instance the stations 65 2 are distinct from the surface 1, and comprise preferably horizontally disposed surfaces or tables which are separated from the inclined surface 1 by beads or flanges 3, which provide means for limiting the downward travel of the packages. If desired, as shown in this figure, spaces 4 may be provided between the stations 2 in which operatives may stand and it will be observed that by reason of the distributing action of 70 the surface 1, the stations 2 may extend or be disposed around a plurality of sides thereof permitting of a number of operatives simultaneously handling the packages. 75 For convenience of description the surface 1 80 may be defined as being "humped", that is, it is not a flat surface but one rather which preferably slopes away from an upper portion thereof downwardly in different directions.

If desired, the rear side of the table may be provided with flanges 5, or the like, to prevent the inadvertent dropping of parcels thereover and I prefer to provide suitable 85 conveying means such, for example, as the belt 6 for delivering the parcels or packages to substantially the uppermost portion 90 7 of the surface 1. This portion 7 may, if desired, be, for a short distance, of somewhat less inclination than the remaining portion of the surface in question but is so shaped that when the packages are delivered thereupon they may either slide thereover under the influence of gravity or may be pushed thereover by succeeding packages. 100 The contour of this portion is such as to cause packages which chance to be upon, let us say, the right hand side of the belt 6, as viewed in Fig. 1, to slide down over the 105 spreading-surface generally toward the 110

right, while those which correspondingly chance to be more or less upon the left hand side of the belt will fall toward the left over the spreading-surface. Others which are 5 practically in the middle of the belt will usually fall directly toward the front of the table, but in substantially any case the action is such that the incoming packages or parcels will quite automatically distribute themselves toward the respective stations. Those 10 packages which are first delivered to the table will, of course, slide down until they engage the beading 3 and will then serve to retain packages to the rear thereof upon the 15 inclined surface so that only as the first packages are removed can succeeding ones descend into engagement with said beading. If desired, the beading may be enlarged or more extendedly flanged as at 8, immediately 20 adjacent the spaces 4 in which the operatives stand so as to prevent packages, by any chance, sliding from off the table into said spaces. It will be noted that the width of the table is very considerably 25 greater than that of the conveying means. The latter may be of any desired type of construction but I prefer to use a belt conveyor of any well known description adapted to the purpose in question.

30 Outside of the stations 2, which are located along the front edge of the routing table, is, in the present case, a conveying belt 9 which rides in a channel 10 in a well known manner. The channel or trough 10 35 may be supported upon suitable uprights 11 and preferably contains both the upper and lower portions of the belt as indicated in the figure.

Where the packages are to be distributed 40 around a plurality of sides of the table it may be, in some cases, found desirable to provide auxiliary belts 12 which may be driven in the direction of the arrows indicated thereon so that they deliver to the belt 9. The operation of this form of the device 45 is as follows: The incoming packages which are delivered by the conveying means 6 are deposited upon the portion 7 of the surface 1 and automatically apportion themselves 50 to the respective stations 2 in the manner indicated. The operatives occupying the spaces 4 pick up the lowermost packages, which are in engagement with the beading or flanges 3-8 and label them according to 55 their ultimate destination, preferably placing thereon the number of the bin or receptacle, the label or stamp being applied while the package reposes upon the surface 1. Thereafter, said packages are placed upon 60 the belts 9 or 12, as the case may be, all of them, of course, ultimately being routed upon the belt 9 from which they may be removed by operatives stationed adjacent the bins not shown since these latter form no 65 part of the present invention.

One great advantage of the present construction is that the package immediately behind the one which has been picked up by an operative for the purpose of being labeled, automatically slides down toward the same operative in almost all cases, so that the general consecutive order of the packages is not materially disturbed. The movement of the packages over the spreading surface is, of course, more or less a step 75 by step one and relatively slow, depending upon the speed of the operative; but a package having once arrived opposite a given operative, remains stationary and convenient to his hand until he removes the same 80 from the surface 1.

In the form of device shown in Fig. 2 the spreading surface 1' is substantially flat but as the packages descend over this surface they will naturally tend to spread 85 themselves toward the respective stations 2 although, admittedly, not so much as in the case previously considered. In this instance, in addition to the beading, I have indicated that the portion of the surface 1' immediately adjacent thereto has the angular disposition thereof, with respect to the horizontal, so changed that there is a tendency to limit the continued movement of the descending packages toward the respective stations. 90 This change of inclination may be regarded, therefore, as a supplementary means for limiting the downward movement of packages. It is not so dependable, however, as the beading in its action and I, hence, usually prefer to provide the latter in addition. It will be obvious, of course, that if the 95 relatively horizontal portion 13 of the surface 1' be of sufficient width, it will serve as an effective limiting means but in such case 100 it will normally require the operative to reach out thereover some distance, whereas when the packages are delivered directly down to the beading, or where such portion 13 is relatively narrow, the said packages 110 are convenient to his hand. It may, in some instances, be found desirable to run the delivering belt 6' substantially parallel to the table in the manner shown in Fig. 3.

To facilitate the spreading or scattering 115 of the packages toward the operatives or "routers" stationed in the several spaces 4, I prefer in such cases to provide the table with deflecting means adapted to unload said packages, from the conveying means 120 6', more or less equably along the upper edge of the surface 1". A very simple means for accomplishing this is the extended spreader or deflector 14 which preferably extends substantially the entire length 125 of the table. The larger packages obviously will usually be the first to unload; being shifted laterally with respect to the belt by the deflector until they lurch over onto the inclined surface 1". The packages of suc- 130

cessively less size will follow substantially in order except where possibly a large parcel may carry a small one with it. It is to be particularly noted, however, that where the spreading means employed is such an extended deflector, the general angle of divergence of the latter from the line of travel of the conveyer should be but small.

The surfaces 1, 1', 1'', may be given an 10 inclination of, let us say, 23° , and I have found in practice that this relatively slight inclination affords most satisfactory results for paper covered parcels and the like.

Having thus described my invention, 15 what I claim is:

1. The combination of a stationary sorting table of sufficient extent to provide a plurality of stations for operatives, the surface of said table being generally inclined 20 to the horizontal at such an angle as to permit of the articles to be handled sliding downwardly, thereover, means for conveying articles toward said table, articles deposited on the latter from said means moving downwardly over said surface by the 25 action of gravity substantially directly toward said stations, means for limiting the downward movement of and retaining said articles substantially stationary at said stations, a series of spaced individual supports 30 adjacent said movement-limiting means, and means extending past said supports for conveying the assorted articles from said table.

2. The combination of a stationary routing table of sufficient extent to provide a plurality of operating stations, means of materially less width than said table for

conveying articles toward and delivering them substantially unacted upon by gravity 40 directly to the table, said conveying means delivering endwise thereof toward said table, said table adapted to spread the so delivered articles over its surface substantially toward said stations, and means for 45 stopping said articles at said stations.

3. The combination of a stationary routing table of sufficient extent to provide a plurality of operating stations, means of materially less width than said table for 50 conveying articles toward and delivering them substantially unacted upon by gravity directly to the latter, said table provided with means for spreading the articles over 55 its surface substantially toward said stations.

4. The combination of a stationary routing table of sufficient extent to provide a plurality of operating stations, means of materially less width than said table for 60 conveying articles toward and delivering them to the latter, said table having a humped surface for spreading the so delivered articles thereover substantially toward said stations, the upper portion of 65 said humped surface being substantially horizontal and said means delivering articles to this portion, whereby to check the motion thereof preparatory to spreading said articles in manner aforesaid.

In testimony whereof I have affixed my signature in the presence of two witnesses.

FREDERICK G. WHITTIER.
